UNITED STATES PATENT OFFICE.

JOHN BERG, OF CHICAGO, ILLINOIS.

REFUSE AND GARBAGE RECEPTACLE.

1,160,566.

Specification of Letters Patent.

Patented Nov. 16, 1915.

Application filed November 2, 1914. Serial No. 869,834.

To all whom it may concern:

Be it known that I, JOHN BERG, a citizen of the United States, and a resident of West Pullman, Chicago, Cook county, Illinois, have invented certain new and useful Improvements in Refuse and Garbage Receptacles; and I do hereby declare that the following description of my said invention, taken in connection with the accompanying sheet of drawings, forms a full, clear, and exact specification, which will enable others skilled in the art to which it appertains to make and use the same.

This invention has general reference to improvements in refuse and garbage receptacles, and it consists, essentially, in the novel and peculiar combination of parts and details of construction, as hereinafter first fully set forth and described and then pointed out in the claims.

In the drawing already referred to, which serves to illustrate my said invention more fully, Figure 1 is a rear elevation of my combined refuse and garbage receptacle; meaning by rear elevation, the view as seen from the interior of the yard, in the fence of which the said receptacle is placed. Fig. 2 is a front elevation or alley view of the same. Fig. 3 is an end elevation thereof.

Fig. 4 is a vertical transverse section in line 4—4 of Fig. 1, and Fig. 5 is a section of a fragmentary detail in line 5—5 of Fig. 4.

Like parts are indicated by corresponding symbols or characters of reference in all the figures of the drawing.

My invention comprises a concrete refuse and garbage receptacle, constructed in parts, properly molded and cast at the factory and shipped in a knocked down condition, with simple interlocking means whereby the same, when assembled, requires no bolts, tie rods, or other media to maintain the apparatus in its erected position.

Correlated with my invention are means in connection with the refuse portion of the receptacle whereby such refuse may be burned in said receptacle without annoyance or fire danger to neighboring property.

Referring now to the drawing in the case, A indicates the invention as a whole; B is the base section; C, the body section, and D the top section. The base section is a plane plate 10 of reinforced concrete, having an upwardly inclined front 11. Laterally extending, and upwardly projecting

lips 12 and 12^a are provided for the base section at the ends thereof, and along the rear edge thereof, adjacent said end lips are ledges 13 and 13^a. Adapted to fit between the end lips 12 and 12^a, resting on the base B, and forced against the end ledges 13 and 13^a is the middle section C having the lower edge of its front wall 14 on the upwardly inclined front 11, along the outer edge thereof, as clearly seen in Figs. 3 and 4. This body section C is cast *en-bloc* from reinforced concrete and is a hollow, substantially rectangular body, having the front and rear walls 14 and 15 respectively; the end walls 16 and 17, and a medial lateral partition 18, to divide the body into two chambers or receptacles 19 and 20 for refuse and garbage, respectively.

Along the front wall 14 of the body C is integrally formed a raised, narrow, longitudinal rail, dado, or surface 21, for reception of hinges 22 and 22^a, to which latter, respectively, are affixed doors 23 and 23^a, closing openings 24, formed in front wall of body C at the lower end of said wall to afford access to the inner chambers 19 and 20. The said doors are locked against accidental opening by latches 25 and 25^a.

Attention is now drawn to the fact that the front and rear walls slope backwardly from the perpendicular. This is merely a matter of choice, and it is to be further remarked that the over all length of the body C is slightly less than the distance between the lips 12 and 12^a, so that said body may fit between said lips with its walls 16, 17, 18 resting squarely upon the base B, and with its rear wall 15 forced against the ledges 13 and 13^a by the action of the front wall 14 resting upon the downwardly inclined surface of the base member 11. The weight of the said body, with the lower edges of its front and lateral walls co-acting with the wall 11 will constantly maintain the body and the base in proper correlation.

In the rear wall 15 of the body, in the lower edge thereof, on either side of the partition 18 are rectangular cutouts 26 and 26^a, the office of the former being to permit the ingress of oxygen as hereinafter described, and the other to allow the exit of flushing water from the chamber 20, when the same is being cleansed.

Resting upon the upper edges of the walls 110

of the body C and flush with the outer surfaces of said walls, is an integrally formed cover D, made from reinforced concrete and possessed of an upstanding ledge 30, which ledge is in effect a continuation of the front wall 14 and is provided as an integral backing for a short hollow stack 31 integrally cast with the cover D, which stack has an axial opening 31^a throughout its length and the thickness of said cover, whereby communication between the refuse chamber 19 and the atmosphere may be had.

Longitudinally along the top face of cover D is cast a ledge 32, to which fastens hinges 33 and 34 supporting closures 35 and 36, which closures are adapted to close openings 37 in the cover D, arranged for the introduction of refuse or garbage into their respective chambers 19 or 20. In order to prevent longitudinal or lateral movement of the concrete cover D upon the body C, the former has two lateral ledges 40 and 41 arranged adjacent the end walls of the body and extending almost the entire width of said cover.

It is intended that this device be set in an opening provided therefor in the average alley line fence and a fragmentary view thereof is shown at 50 in Figs. 1 and 3, in the latter of which it will be noted that the inclined wall 11 of the bottom B projects beyond said fence into the alley. The object of this is to facilitate the work of the garbage gatherers in removing the contents of the chambers 19 and 20, as it is much easier for the gatherer to slide his garbage shovel down an inclined bottom, than along a flat bottom, as will be easily understood.

It is to be understood that the chamber 19 with its oxygen inlet 26 and products of combustion outlet 31 is initially intended as a burner for paper and all other easily combustible refuse, such as grass clippings, and other refuse not essentially garbage. But by the introduction of a suitable burner of proper type for crude oil or kerosene, the same may be converted into a garbage incinerator, the walls of the device being amply thick and sufficiently reinforced to withstand the temperature of incineration.

While I have herein disclosed the preferred method of practising my invention, I desire it understood that I may make such changes or alterations therein, as may suggest themselves to one skilled in the art or permitted under the doctrine of equivalents.

Having thus fully disclosed my invention I claim as new and desire to secure to myself by Letters Patent of the United States:—

1. In combination, a base plate having an upwardly inclined forward portion, an independent hollow open ended body section composed of walls, the lower edges of which are adapted to rest on said base and its inclined member to force said lower edges of

the body section into closer contact with said base, and a cover section superimposed on said body section, and means in connection therewith preventing longitudinal and lateral movement of said cover on said body.

2. In combination, a base plate having upstanding ledges upon its rear edge thereof and an upwardly inclined forward portion, an independent hollow open ended body section composed of walls, the lower edges of which are adapted to rest on said base and its inclined member, whereby the rear wall of said body section is forced against said ledges by the weight of the body resting upon said inclined forward portion, a cover section superimposed on said body section, and means in connection therewith preventing longitudinal and lateral movement of said cover on said body.

3. In combination, a base plate having an upwardly inclined forward portion, an independent, hollow, open ended section composed of walls, the lower edges of which are adapted to rest on said base and its inclined member to force said open ended section into closer contact with said base, and a cover section superimposed on said body section.

4. In combination, a base plate having upstanding ledges upon its rear edge thereof, and an upwardly inclined forward portion, an independent, hollow, open ended body section composed of walls, the lower edges of which are adapted to rest on said base and its inclined member, whereby the rear wall of said body section is forced against said ledges by the weight of the body resting upon said inclined forward portion, and a cover section superimposed on said body section.

5. In combination, an integrally formed base plate having an upwardly inclined forward portion, lateral upstanding lips along the lateral margins of said base plate, said margins terminating in upstanding, inwardly extending ledges on the rear edge of said base, an integrally formed, open ended body section comprised of marginal and partition walls, fitting between said lips, upon said base, the forward wall of said body being possessed of openings thereinto and closures therefor, the rear wall of said body having cutouts along the lower edge thereof, and a cover section superimposed upon said body section.

6. In combination, an integrally formed base plate having an upwardly inclined forward portion, lateral upstanding lips along the lateral margins of said base plate, said margins terminating in upstanding, inwardly extending ledges on the rear edge of said base, an integrally formed, open ended body section comprised of marginal and partition walls, fitting between said lips, upon said base, the forward wall of said body being possessed of openings thereinto and closures

therefor, the rear wall of said body having cutouts along the lower edges thereof, an integral cover section superimposed upon said body section and interlocked therewith, said 5 cover having an integral, upstanding front wall forming a continuation of the front wall of said body section, and an integrally formed hollow stack in connection with said wall and communicating with the interior

of said body section, there being openings 10 in said cover and closures therefor.

In testimony whereof I have hereunto set my hand in the presence of two subscribing witnesses.

JOHN BERG.
